[57] CLAIM

The ornamental design for a sun lamp, as shown and
described.

DESCRIPTION

FIG. 1 is a perspective view of a sun lamp showing my
new design, illustrating the front, top and right side
surfaces; the left side surface is substantially a mirror
image of the right side surface. The bottom surface is
substantially a mirror image of the top surface;
FIG. 2 is an enlarged front elevation thereof;
FIG. 3 is a front elevation of a second embodiment
showing my new design;
FIG. 4 is a left side elevation thereof, the right side
being the mirror image;
FIG. 5 is a top plan view thereof;
FIG. 6 is a bottom plan view thereof;
FIG. 7 is a rear elevation view common to both em-
bodiments.
